PERCIVAL V. WADLEIGH, OF NEEDLES, CALIFORNIA.

FLYING-MACHINE.

No. 926,913.

Specification of Letters Patent.

Patented July 6, 1909.

Application filed July 17, 1908. Serial No. 444,102.

To all whom it may concern:

Be it known that I, PERCIVAL V. WADLEIGH, a citizen of the United States, and a resident of Needles, in the county of San Bernardino and State of California, have invented a new and Improved Flying-Machine, of which the following is a full, clear, and exact description.

This invention relates to flying machines, 10 and especially to flying machines of the aeroplane type.

The object of the invention is to produce a flying machine of simple construction which is provided with mechanism for raising 15 the same to the desired elevation, and having independently operated propellers for advancing the machine.

The invention resides in the construction of the lifting mechanism and propelling 20 mechanism, and also in the mechanism for guiding the machine.

The invention consists in the construction and combination of parts to be more fully described hereinafter and particularly set 25 forth in the claims.

Reference is to be had to the accompanying drawings forming a part of this specification in which similar characters of reference indicate corresponding parts in all the figures.

30 Figure 1 is a side elevation of a flying machine constructed according to my invention, certain parts being broken away and shown in cross section; Fig. 2 is a plan, certain parts being broken away and shown in cross section; Fig. 3 is a vertical cross section through the flying machine, on the line 3—3 of Fig. 1, and illustrating the special mechanism for raising the machine, the propellers being represented broken away, and Fig. 4 is a 35 view similar to Fig. 3, but showing the lifting mechanism in a different position.

Referring more particularly to the parts, 1 represents the body of the flying machine which has the form of a channel or shell in 40 cross section, as shown in Figs. 3 and 4. Near its middle point, the sides of this shell are connected by a cross bar 2, upon which a lifting engine 3 is mounted. The piston of this engine is connected with a crank 4, 45 which is attached to a longitudinally-extending shaft 5, the ends of the said shaft being rotatably mounted in pedestal bearings 6, near the ends of the machine. At the ends of the body, vertically disposed 55 guide frames 7 are provided. Each of these frames consists of a main post or stanchion

8 disposed centrally, and side posts or guides 9. These guide frames 7 support at their upper ends an aeroplane 10, which is composed of two planes 11 and 12, which incline 60 downwardly from the central axis of the body. These planes are formed with a plurality of openings 13, at the upper edges of which are pivotally mounted a plurality of shutters 14. These shutters depend through 65 the openings 13 and their upper edges project slightly above the pivot points, and are formed with counterweights 16. As shown, the point of suspension 15 of each shutter is near the upper edge thereof, so that under 70 the action of gravity the shutters are nearly balanced, but they will assume the closed position shown in Fig. 3, when air pressure is exerted upon their under sides. When the machine is rising, however, they will fold 75 downwardly in a vertical position, as shown in Fig. 4, so as to allow the air above the machine to pass down through the openings 13.

On the central posts 8, I provide slides 17, 80 which are guided upon the posts by means of guide brackets 18, as indicated. To these slides 17, pitmen or connecting rods 19, are attached, and the lower ends of these rods are connected pivotally to cranks 20 attached to the ends of the shaft 5. At the upper ends of the slides 17, cross heads 21 are formed, and these cross heads are provided with pivotal wings 22 which are pivoted to the cross heads at 23. These pivot points 23 85 are disposed inwardly of the middle points of the wings 22 so that the wings tend to hang downwardly in the position indicated in dotted lines in Fig. 3. The upper edges of the wings are beveled so that they are adapted to come together upon the downward stroke of the cross head, and as indicated in Fig. 4, the lower edges of the wings 22 are connected by cords 24 which tend to prevent the wings from bending outwardly at their 90 lower edges. By means of the mechanism described above, the machine may rise to a height in the air.

The propelling mechanism for advancing the machine will now be described: Referring especially to Figs. 1 and 2, on the sides 25 of the shell or body 1, I provide a plurality of brackets 26 which support a plurality of arms 27, which normally extend outwardly from the body, as indicated in Fig. 2. 110 These arms are all connected by a parallel rod or link 28 which is pivotally attached to

the arms by pins 29, as shown. These arms 27 carry propellers 30, and these propellers consist of blades 31 and 32 which are connected by hinge connections 33 with the upper and lower sides of the arms, as indicated in Fig. 1. The forward edges of these blades are provided with counterweights 34 which counterbalance the bodies of the blades in such way that on the rearward stroke, or 10 driving stroke, the blades will open and hold themselves in the position shown in Fig. 1, but on the other stroke, they will collapse and move through the air without offering great resistance. As indicated in Fig. 1, 15 when the blades are open they are disposed at an angle to each other so as to catch the air and act as efficient propellers. In order to drive these propellers, the links 28 are connected with the outer arms of levers 35, 20 which extend through the side walls of the shell, and these levers are connected by links 36 with piston rods 37 operating in longitudinally disposed cylinders 38, placed abreast of each other in the rear part of the body, as indicated in Fig. 2.

In order to steer the machine, I provide a steering nose 39, which has a vertically disposed vane 40 and a horizontally disposed vane 41. These vanes are slightly tapered 30 at their forward ends, as shown. The nose is mounted in the forward end of the body in a central position by means of a ball 42 which is received in a socket 43, as indicated. By means of this ball and socket, the nose may 35 be made to assume any desired angle of position with respect to the body. A steering tail or rudder 43^a is provided which is attached to the rear end of the body by means of a ball 44 received in a socket 45, similar to 40 the corresponding mounting for the nose. This tail 43^a is formed with a vertical vane 46 and a horizontal vane 47. This tail is similar in form to the nose 39, except that it is longer and enlarged slightly toward its rear 45 end. At the forward end of the body, I provide a bracket arm 48, to which a tiller 49 is pivotally attached in such a way that it will swing in a horizontal plane. The arms 50 of this tiller are connected by cords 51 with the 50 rear edges of the horizontal vane 41 of the nose. These arms 50 are also connected by crossed cords 52 with the forward edges of the horizontal vane 47 of the tail. From this arrangement, it is possible to move the 55 nose and tail in a horizontal plane simultaneously by means of the tiller 49. At the rear end of the body, a bracket arm 53 is provided, which is similar to the bracket arm 48, and in this bracket arm, a tiller 54 is mounted, which swings in a vertical plane and the arms 55 of this tiller are connected by cords 56 with the forward edge of the vertical vane 46 of the rudder or tail. To the arms 55 are 60 also attached crossed cords 57 which extend forwardly and attach to the rear edges of the

vertical vane 40 of the nose. From this arrangement it will be evident that by means of the tiller 54, the nose and tail may be moved simultaneously in a vertical plane. It will also be evident that on account of the crossed cord arrangement, when the nose 39 is 70 pointed downwardly at its forward end, the tail 43 will tip downwardly at its rear end, which will tend to direct the machine downwardly. In the same manner, when the nose 39 is 75 pointed toward the right, the rear end of the tail will also move toward the right, and this will tend to direct the course of the machine toward the right.

In the mode of operation of the machine, 80 by operating the engine 3 so as to rotate the crank 4, the slides 17 will be reciprocated, and on the up stroke the wings 22 will fold into the position indicated by the dotted lines shown in Fig. 3. When the wings have 85 reached the upper limit of their stroke, they are closed by means of inclined strips 58 which form an angle to each other and which are attached to the upper part of the guide frame, as shown. The upper edges of the 90 wings strike these strips so that the wings open into the position shown in Fig. 3, just before the downward stroke begins. On the down stroke, the wings 22 catch the air under them and maintain themselves open on account of the excessive area on the outer portions, that is, beyond the pivot points 23. On the down stroke, the machine will rise 95 and the shutters 14 will open so as to lessen the air resistance, and permit the air above the machine to pass down. On the up stroke the shutters 14 close, so that the aeroplane 10 tends to support the machine in the air. In this way the engine 3 can be operated before the desired height is reached, and then 100 the cylinders 38 can be operated so as to drive the propellers.

The manner of steering the machine will appear clearly from the foregoing description of the steering mechanism. The steering cords are passed through openings 59 formed in the ends of the body, as indicated most clearly in Figs. 3 and 4.

While I have described the motors which 115 drive the propellers, and which raise the machine, as engines, it should be understood that I may use motors of any kind for this purpose.

Having thus described my invention, I claim as new and desire to secure by Letters 120 Patent, —

1. In a flying machine, in combination, a body, guide frames supported thereupon, slides guided on said guide frames, a pair of pivoted wings disposed at an angle to each other and mounted on said slides, adapted 125 to fold on their upward movement and adapted to open on their downward movement to catch the air, and an aeroplane also mounted on said guide frames having open-

ings and shutters adapted to fold into said openings.

2. In a flying machine, in combination, a body, guide frames mounted thereupon, 5 slides running on said guide frames, a pair of inclined folding wings pivotally mounted on said slides, disposed at an angle to each other abutting at their adjacent edges on the down stroke and adapted to fold on the 10 upward stroke of said slides, means for reciprocating said slides, a pair of aeroplanes mounted on said frame and disposed at an angle to each other, said aeroplanes having openings therein, and folding shutters 15 mounted in said openings.

3. In a flying machine, in combination, a body, guide frames mounted thereupon, slides reciprocating on said guide frames, wings pivoted eccentrically on said slides, 20 whereby said wings tend to open out on the down stroke of said slides, said wings being adapted to come together at their adjacent edges to form an angle, and means for reciprocating said slides.

25 4. In a flying machine, in combination, a body, guide frames mounted thereupon, slides running in said guide frames, wings pivotally mounted eccentrically on said slides, whereby said wings are adapted to 30 fold on the upward stroke of said slides, said wings being adapted to come together at their adjacent edges on the downward stroke to form an angle, means for reciprocating said slides, aeroplanes mounted on said guide 35 frames, disposed at an angle to each other and having openings therein, and a plurality of shutters mounted in said openings, adapted to open when said machine rises and adapted to be closed by air pressure acting from the 40 under sides of said aeroplanes.

5. In a flying machine, in combination, a body, a plurality of arms pivotally mounted

on the sides thereof, blades having joints connecting the same to said arms, forming an angle to each other when open, said wings 45 being adapted to open on the rearward stroke of said arms and adapted to fold on the forward stroke of said arms, said wings having counterweights for the bodies thereof disposed forward of the axes of said joints, 50 links connecting all of said arms on each side of said body, and means for actuating said links.

6. In a flying machine, in combination, a body, a plurality of arms pivotally mounted 55 on the sides thereof, means for actuating said arms in unison so as to swing the same in a horizontal plane, and blades having a hinge connection with the upper and lower sides of said arms and adapted to open to 60 form an angle therebetween on the rear stroke of said arms, said blades having counterweights forward of said hinge connection and abutting at their forward edges when in their open position. 65

7. In a flying machine, in combination, a body, guide frames mounted thereupon, slides reciprocating on said guide frames, wings pivotally mounted on said slides, adapted to open to form an angle to each 70 other on the downward stroke of said slide and adapted to fold on the upward stroke of said slide, and members attached to said guide frames and adapted to move said wings into their open position at the end of the up 75 stroke of said slides.

In testimony whereof I have signed my name to this specification in the presence of two subscribing witnesses.

PERCIVAL V. WADLEIGH.
